Primary Examiner—Cathron C Brooks*Assistant Examiner*—Kevin K Rudzinski(74) *Attorney, Agent, or Firm*—Lawrence E. Laubscher, Jr.(57) **CLAIM**

The ornamental design for a lamp stand, as shown and described.

DESCRIPTION

FIG. 1 is a front perspective view of the lamp stand illustrating my design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an enlarged top plan view of the head portion shown in FIG. 6, shown separately for clarity of illustration;

FIG. 9 is an enlarged bottom plan view of the head portion shown in FIG. 7, shown separately for clarity of illustration;

FIG. 10 is an enlarged front elevation view of the head portion shown in FIG. 2, shown separately for clarity of illustration;

FIG. 11 is an enlarged right side elevation view of the head portion shown in FIG. 5, shown separately for clarity of illustration; and,

FIG. 12 is an enlarged front perspective view of the head portion shown in FIG. 1, shown separately for clarity of illustration.
